COMBINING MACHINE

Charles C. Willis, Bound Brook, and Sterling W. Warner, Somerville, N. J., assignors to John Waldron Corporation, New Brunswick, N. J., a corporation of New Jersey

Application August 27, 1935, Serial No. 38,066

5 Claims. (Cl. 164—68)

This invention relates to combining machines.

In various industries cardboard, strawboard, or other forms of boards are covered with paper or the like. It has been generally customary to cover one side and then run the board again through the machine to cover both sides of the board. In covering the cardboard and the like many difficulties occur. When a web of lining or covering paper has the glue applied there is a stretch to the paper which makes it difficult for it to be applied smoothly to the board. The cutting of the wet web of covering paper also has difficulties in that considerable wastage may be involved. Again difficulties are occasioned by the variation in the thickness of the cardboards that are required to be covered.

One of the objects of this invention is to provide a machine for combining a sheet of paper with boxboard, cardboard, or the like.

Another object of the invention is to simultaneously combine two sheets of paper with boxboard and the like covering two sides thereof.

Still another object of the invention is to provide a machine operating at relatively high speed and with small wastage for the combining of two sheets of paper with boxboard or the like.

Other objects will appear more fully hereinafter.

Referring to the drawings:

Figure 1a is a longitudinal side elevation of a portion of a device embodying the principles of our invention.

Figure 1b is a longitudinal view in side elevation of the balance of a device embodying the principles of our invention.

Figure 2 is a sectional view of the web smoothing rolls showing cam 16 as an adjustable cam.

Figure 3 is a view in elevation of the web smoothing roll with parts broken off. In this view cam 16' is shown as a fixed cam.

Figure 4 is a sectional view of Figure 2 along the line 4, 4, looking in the direction of the arrows.

Figure 5 is a sectional view of Figure 2 along the line 5, 5, looking in the direction of the arrows.

Figure 6 is a view in elevation of the holding pin securing the core 97 to the cam disk 16.

Figure 7 is a view in elevation of the cutter roll.

10, of Figure 12, looking in the direction of the arrows.

Figure 11 is a detail view of the cutter control mechanism and gearing.

Figure 12 is a view of Figure 11, along the line 12, 12, looking in the direction of the arrows.

Figure 13 is a longitudinal sectional view of the cutter control valve.

Figure 14 is a cross sectional view of Figure 13 along the line 14, 14.

Figure 15 is a detail view of the roll adjustment mechanism.

Figure 16 is a cross sectional view partly in elevation along the line 16, 16, of Figure 15.

In carrying out my invention, I provide a frame 1 with a table 2 upon which the boxboard stock is fed.

Feed rolls 3, 3', 4, 4', deliver the cardboard stock between linings 5, 5'.

Webs 5 and 5' coming from unwind rolls 6, 6', passing over idler rolls 7, 7', and then over gumming or gluing rolls 8, 8'.

The method of applying the glue, paste or other adhering material is well known in the art and therefore need not be further described.

The webs 5, 5', then pass over a particular form of straightening or ironing roll as shown in detail in Figures 2, 3, 4,

5 and 6. Rolls 9 smooth out the gummed paper so that it may be applied evenly and without wrinkles.

The rolls 9 are cylindrical and are formed exteriorly of strips of smooth metallic elements of different lengths in order that the junction of the elements do not fall in the same plane.

These metallic elements 10 are secured to cylinder heads 11 by wedge shaped lugs 12 moving in corresponding wedge shaped channel 12' in the surface of cylinder heads 11.

On each of said metallic elements or segments 10 are secured, by bolts 14, collar bearings 15.

The bearings 15 are adapted to bear against a cam or disk 16.

This cam or disk 16 is at an angle to the axis of roll 9 so that when cylinder 9 is rotated the segments 10 are caused to move toward and from the segment on the same line creating a sidewise movement of the segments away from each other during part of the rotation and toward each other during the balance of the rotation.

Adjustment screws 17 are adapted to vary the extent of the motion.

Two pins 98 secure disk 16 to core 97.

By such device the moistened paper is smoothed and stretched so that when the webs 5, 5', are applied by applying

rolls 80, 81, to the board stock the covering paper is smooth and without wrinkles.

The stock after it is covered then passes between rolls 80, 81.

These rolls may be heated or a drying medium,

such as heated air, may be blown upon the web or the entire machine may be in a conditioned drying atmosphere. After the webs have been combined and dried they reach the rear of the machine where the cutting of the webs 5, 5', takes place. At this time the web coverings may or may not be completely dried out and the material is travelling at a relatively high rate of speed making it impossible to cut the webs manually. In addition, the time element practically eliminates all forms of shear cutters with the exception of a roll cutter. The question of wastage prevents the use of a straight edge rotary type of cutter, which to avoid excessive vibration or jar, must be placed at a predetermined angle on the roll, the angle being dependent upon the speed of travel of the material, and therefore any change in the speed of travel prevents the use of such knife. In addition, the wastage of the material in the cutting is important. Also in order to make a clean cut the edge of the material should be supported. With a rotating knife any form of support must permit the entrance and egress of the knife and with the usual serrated knife there is too little support for the material causing tearing to take place as the material is forced into the slot without separation or cutting. I propose therefore to provide a special form of cutting mechanism as shown in detail in Figures 7, 8 and 9. This cutting mechanism comprises cylinder 20 mounted on shaft 21 and has a saw tooth cutter knife 22 inserted radially in cylinder 20 and protruding beyond the surface of the circumference. The blade 22 may be removably secured therein such as by a wedge block 23 with securing bolts 24 threaded into roll 20. A rubber grip 25 may be inserted back of the blade 22. The purpose of the rubber grip 25 is to firmly hold the material as it is cut by knife 22 against the lower roll 26. Lower roll 26 is grooved to accommodate two adjacent blocks 27, 28, which are screwed to roll 26 by screws 29. Blocks 27, 28, have a channel 30 therebetween. The walls of the channel formed in serrated grooves corresponding to the teeth of the cutter 22 in shape and size but located so that the top of each tooth of the blocks 27, 28, correspond in position to the bottom of each tooth of serrated blade 22. By this formation and positioning the clearance all around the teeth of blade 22 is the same thereby permitting of a complete support of webs 5, 5', during the cutting operation. By means of such support a clean cut can be obtained. In addition, as blade 22 is a straight blade there is a minimum of wastage in the cut made. The form of channel 30 produces a true shearing action in connection with the teeth of cutter 22. Also a plurality of webs may be cut since the supporting elements, blocks 27, 28, support the lower and upper webs of material during the cutting operation and the minimum clearance of the teeth of cutter 22 prevents the webs 5, 5' from being pressed into slot 30 as only the blade itself is permitted to enter to shear through the travelling webs.

Such construction requires the minimum of mass for operation and is therefore particularly adapted for use in connection with the automatic cutting of webs of material where the control mechanism which actuates the roll cutters is initiated by the goods themselves. It is, therefore, possible to utilize friction drives for the rolls 20, 26, thereby securing the possibility of continuous or intermittent rotation of the cutting roll. If they are driven frictionally any form of mecha-

nism restraining their rotation with a quick release immediately starts rotation of the rolls and predetermined cutting. Such a mechanism enables the goods to be made in predetermined different lengths with accurate cutting of the web between the cardboard lengths of boxboard stock. With this type of cutting mechanism no vibration or jar takes place as is the case where cutters cut through a web of material against a hard surface. With this type of cutter there is no lifting of the cutter roll by the material. The lightness of the mass of the cutting mechanism reduces the power consumption to the minimum for the particular operation.

A proper control for the cutter mechanism is required. As the pasting portion of the machine operates at a relatively high linear speed, the problem of the intermittent cutting without too much wastage is rather difficult. The sheets of cardboard should be as close together as possible since the further they are apart the greater the wastage and in the case of double combining the wastage is double, hence quick action and of a positive type must be the characteristic of the control mechanism. The accurate synchronization of the cutting of the webs with respect to each boxboard makes it desirable to have the boxboard sheets themselves automatically initiate the control mechanism.

Referring particularly to Figure 10 and Figures 12 to 14 inclusive:

The cardboard sheets are spaced to permit the web to furnish an initiation means for the control mechanism. This separation of the cardboard stock is maintained uniformly in feeding to the machine and the distance is as small as possible preferably not exceeding three-quarters of an inch. A small roller 31 rides on the upper web 5 of the material after it has come from the pasting and drying processes. As the end of each boxboard sheet passes under roll 31, the latter drops in the depression between the boxboard sheets since the web 5 no longer supports it on the same level. The material is travelling at a relatively high linear velocity necessitating the correct timing of the starting of the cutters to function in order that they may cut the webs when the end of the cardboard stock reaches the cutter 22. Roll 31 is carried by arms 32 of bell crank lever 33 which latter is supported by shaft 34. Arm 35 of bell crank lever 33 carries adjacent its end adjustment screw 36. The latter is adapted to trip lever 37 which is pivoted at 38 and carries at its other end a seat 39 which covers outlet 40 of pneumatic line 41. A light tension spring 42 normally maintains seat 39 over opening 40. The uncovering of opening 40 to the atmosphere initiates the action of pneumatic valve 43. The latter consists of a valve bar and housing 44' which has valve guides 45, 46. Valve 47 is limited in movement between valve seats 48, 49. To the lower end of valve stem 50 is screwed a valve base 51 below which is a flexible air tight diaphragm 52 secured over chamber 53 in valve housing 44'. A bellows 54 is formed by a movable board 55 hinged at 56 to valve housing 44'. The bellows 54 has the usual air tight rubber cloth or other flexible material covering 57. The bellows 54 operate against the tension of spring 58. Chamber 59, being a vacuum chamber, is exhausted in any well known manner, such as by the outside vacuum pump or other device through tube 44. Upon the unseating of seat 39 and the uncovering of opening 40 atmospheric pressure is admitted through 75

pneumatic line 41 to chamber 53. Pressure is thereby exerted against diaphragm 52 which pressure is transmitted through valve base 51 raising the base and moving valve 47 thereby opening chamber 62 to suction action (chamber 59) and causing the movement of board 55 to actuate lever 60 to release the cutting rolls 20, 26, to permit them to rotate. Rolls 20, 26, are of a predetermined size whereby when they have completed a revolution the knives cut the material at a predetermined point between the cardboard stock. After roll 21 rides up upon the next cardboard sheet covered by web 5, spring 42 reseats seat 38 over opening 40. The closing of pneumatic line 41 permits the bleeding of air through small opening 61 into chamber 59 causing a balance of pressure whereby valve 47 shifts from seat 48 to seat 49, admitting atmospheric air through passage 62 to bellows 54 thereby actuating rocking lever 60 about its pivot 63 causing its latch end 64 to again engage cam 74 to maintain rolls 20, 26, from rotation. Hole 61 quickly equalizes the pressures in chambers 59 and 53 to permit quick return of valve 47 when the pneumatic line 41 is closed.

Cutting roll 20 is keyed to shaft 21 and cutting roll 26 is keyed to shaft 65. Shafts 21 and 65 are connected by gears 101 and 102. Gear 66 and cam 67 are likewise keyed on shaft 65. Stationary shaft 72 carries gear 103 which is free to rotate. One-half of friction clutch 73 is secured to gear 103. The other half 73' has a long hub on which is mounted gear segment 69, cam 70, cam 100 and clutch throwout collar 104. Gear 71 is free to rotate on stationary shaft 105. One-half of friction clutch 76 is mounted on hub of gear 71. The other half 76' of friction clutch 76 has a round hub on which is mounted cam 74, cam 106 and cam 75. The two halves of clutch 76 are held together by means of compression spring 107. Clutch throwout yoke 79 normally holds the two halves of clutch 73 apart by action of wedge end of slide 78. One-half of clutches 76 and 73 are rotated by means of gear train 110, 103, 111, 77. When end of lever 60 engages in notch of cam 74, clutch 76' with cams 74, 106 and 75, are held stationary. Clutch 73' with gear segment 69, cams 70 and 100, are also held stationary by means of lever 112 engaging in notch of cam 100 cutting rolls 20 and 26 are held in their predetermined position by means of cams 70 and 67 interlocking. When lever 60 releases cam 74 by action of pneumatic 54, cams 74, 106 and 75 rotate because the two halves of friction clutch 76 are in contact by action of spring 107. When cam 106 rotates cam 100 is released through the action of lever 113, link 114 and lever 112, at the same time permitting wedge 78 to move downward by the rotation of cam 75 which in turn releases yoke 79 engaging clutch 73 and 73' by action of compression spring 108. Gear segment 69 and cam 70 now rotate which in turn rotates shaft 65 by the meshing of gear segment 69 with gear 66 and the releasing of cam 67 by cam 70. As shafts 65 and 21 are connected by gears 102 and 101, cutting rolls 26 and 20 rotate until again stopped through the re-engaging of lever 60 in notch of cam 74. The rolls are then in their predetermined position preparatory to a new movement being initiated by the unseating of 38 over opening 40.

The boxboard or cardboard stock varies in thickness and hence it is necessary to have some

means of adjustment to accommodate the machine for the different thicknesses.

Referring to Figures 1a, 1b, 15, 16, rolls 80 can be adjusted with respect to the horizontal plane and for parallelism with rolls 81 by means of adjustment screws 82, rolls 80 having shafts 83 journaled in bearing blocks 84 sliding in frame 1, adjustment screws 82 being threaded through bearing blocks and bearing against cam block 85. This is the usual form of adjustment. In addition, according to this invention, all the rolls 80 may be simultaneously raised or lowered to accommodate the different thickness of boxboard or cardboard stock thereby eliminating the necessity of adjusting each roll every time there is a different run of stock. To make the second adjustment handwheel 86 is rotated in either direction as desired. Handwheel 86 is secured to shaft 87 carrying gear 88 which meshes with gear 89 on shaft 90. The latter carries worm 91 which drives wormwheel 92. The rotation of wormwheel 92 rocks yoke 93 either to the right or left in accordance with the movement of handwheel 86 and its train of gearing. The movement of yoke 93 is transmitted to roller 94 which is secured to sliding rods 95. Rods 95 carry wedges 96 on which ride cam blocks 85. As wedges 96 move to the right they raise cam blocks 85 and through screws 82 lift bearing blocks 84, shafts 83, and rolls 80. And similarly the reverse turning of handwheel 86 lowers rolls 80. As the adjustment is a micrometer type of adjustment very accurate and quick adjustments may be made, thereby obviating the old form of individual roll adjustment which is used in this invention only for the initial leveling up of the rolls upon installation or by reason of bearing wear.

It will thus be seen that there has been provided a machine for combining on one or both sides of cardboard or boxboard stock of a web or webs of paper or other material wherein the web is smoothly applied at a relatively high rate of speed and automatically severed after the application of the web or webs with the minimum of wastage and wherein different lengths of stock and different thicknesses may be covered with quick adjustment of the machine for such accommodation.

What we claim is:

1. In a combining machine for combining a web of material with sheets of boxboard, means for cutting said web at the end of each boxboard sheet, said cutting means including a cylinder, a saw tooth cutter knife protruding radially from said cylinder, blocks having a channel therebetween, the walls of the channel serrated to correspond to the teeth of the cutter knife whereby the web is supported around each tooth at the time of the cutting.

2. In a combining machine for combining webs of paper with sheets of boxboard, means for cutting the webs, said cutting means including a cylinder, a saw tooth cutter knife protruding from said cylinder, a serrated slot in a block for supporting the webs during the cutting operation and to prevent the webs being pressed into the slot by the cutter knife teeth.

3. In a combining machine for combining webs of material with cut sheets, means for cutting the webs, pneumatic control means for controlling said cutting means, means for initiating the action of the pneumatic control means by the ends of the boxboards.

4. In a combining machine for combining a web of paper to sheets of boxboard, means for cut-

75

ting the web, means for frictionally driving the cutting means, means for restraining the action of the cutting means, and means for releasing the cutting means for cutting operation.

5. In a combining machine for combining a web of material to sheets of boxboard, means for cutting the web, means for frictionally driving the cuttings means, means for restraining the opera-

tion of the cutting means, means to quickly release the restraining means, said quick release means initiated by the ends of the boxboard sheets to predeterminedly commence the operation of the cutting means, for predetermined cutting of the web.

CHAS. C. WILLIS.
STERLING W. WARNER.
